UNITED STATES PATENT OFFICE

CARL DECKER, OF KNIELINGEN, NEAR KARLSRUHE, GERMANY, ASSIGNOR TO THE FIRM
HENNEFER MASCHINENFABRIK C. REUTHER & REISERT MIT BESCHRANKTER
HAFTUNG, OF HENNEF-ON-THE-SIEG, GERMANY

AUTOMATIC FEED WEIGHER

Application filed August 2, 1929, Serial No. 382,994, and in Germany December 27, 1926.

The subject of this invention is an automatic feed weigher with a main feed and a dribble feed for completing the weight, in which, for the purpose of obtaining exact measurement of the weight, the vibrations of the beam set up during the main feed are prevented by a detaining device and in which the release of the part of the weigher detained by the detaining device is effected 5 after a time interval by a retarding device, whereby the commencement of the remaining portion of the downward movement of the receptacle for the material is delayed, and the completion of the feed may be effected 10 while the beam remains steady.

The device of the present invention is of simpler construction than known devices of this kind while the operation is substantially improved so that the rapidity of the successive 20 weighing operations may be substantially increased even with weighers of large size and serving to weigh large quantities.

In the construction shown the retarding device is combined with the detaining device 25 in a rotatable or oscillating structure which by a single retarding movement effects the release of the arrested member, such as the receptacle.

A still further object of the invention is 30 to provide a construction wherein the period of oscillation can be varied so as to take care of loads of different amount and materials of different kinds.

With these and other objects in view which 35 will appear as the description proceeds, the invention consists in the arrangement and combination of parts detailed below, claimed in the claims and shown in the drawing, in which

40 Figure 1 is a partial elevational view of a scale illustrating one form of the invention;

Figure 2 is an elevational view of the arresting and damping member shown in Figure 1 in another position allowing the movable portion of the scale to descend further during the dribble feed;

Figure 3 is an elevational view of a modified construction for the retarding and damping member, and

50 Figure 4 is an elevational view of a still

further modification of such retarding and damping member.

As above pointed out, this invention relates to scales in which provision is made for a main feed and a dribble feed for closely approximating the correct weight. Scales of this type are shown in the following patents: M. E. Reisert 941,588 Nov. 30, 1909 55 M. E. Reisert, 376,965 Jan. 24, 1888 M. E. Reisert 652,642 June 26, 1900 M. E. Reisert 60 585,785 July 6, 1897.

The weighers illustrated have a wide passage 1 for introduction of the material permitting rapid weighing operations with rapid feed of the material. As usual there 65 are provided an inner shutter 2 for cutting off the main feed and an outer shutter 3 for terminating the dribble feed.

In the construction according to Fig. 1 the arm 23 is pivotally suspended to rock about a knife-edge 5 (or pivot) fixed on the weigher frame, the said arm having at each side of and above its fulcrum a weighted arm 23a. That weighted arm 23a extending above the fulcrum carries a weight biased towards the 70 right hand side and tending to impart to the lower part of the arm 23 slow rotation to the left. The two weighted side arms 23a impart a certain inertia to the arm 23. In the lower part of the depending arm 23 is a 75 notch 24 engaged by the part to be detained, that is, the pin 7 fixed to the receptacle 6 and, the said notch engaging the pin 7 from below. When in its upper position the pin prevents rotation of the arm 23 to the left. The lower 80 portion of the notch 24 is adjoined at the right hand side to an open-ended slot 25 the boundaries of which are constituted by two lateral prolongations 26, 27 of the arm 23. The upper edge of the slot 25 extending towards the open end is increasingly spaced 85 from the pivot 5 of the arm 23, that is, presents a curve of progressively increasing radius as will appear from consideration of the chain-dotted line α in the figure.

90 The mode of operation is as follows:—

When during the main feed the receptacle 6 moves downwards the pin 7 descends in the notch 24 and abuts on the lower boundary 95 thereof whereby further descent of the recep-

- tacle 6 is temporarily prevented. The arm is now free from the pin 7 at the upper part of the notch, and moves slowly in clockwise direction so that the slot 25 travels over the pin 7, the upper edge of the extension 26 constituting a continuation of the arresting surface. The lower edge of the extension 27 intercepts the pin 7 vibrating vertically in consequence of the impact of the material falling into the receptacle, and in consequence of the increasing distance of the edge 27 of the slot from the pivot of the arm 23 the amplitude of vibration of the pin is progressively decreased. The receptacle 6 is thus brought to rest when the pin 7 is released from the lower extension 26 of the arm 23. The receptacle can now complete its downward movement (Fig. 2) as the weight is completed by the dribble feed.
- 20 After the receptacle has been emptied the pin 7 is again opposite the slot 25, and by the action of the eccentric edge of the extension 27 on the pin 7 the arm 23 is restored to the position in which the pin 7 is located in the upper part of the notch 24.

The variant illustrated in Fig. 3 differs from the construction last above described in respect that the notch 24 and the slot 25 are located above the knife edge or pivot 5. The actuation of the arm 23 to rotate the same slowly to the left is effected by reason that the centre of gravity of the mechanism is located above the pivot 5 and disposed to the left adjacent to the vertical plane containing the pivot 5. The weight 28 gives the desired inertia to encure slow initial movement of the system.

In this variant the slot 25 is so arranged that the upper boundary thereof is at a progressively decreasing distance from the pivot of the arm 23.

Instead of the arm 23 the member effecting the arrest and the retardation may be constituted by a disc as shown in Fig. 4 in which the slot 25 communicating with the notch 24 may open at the edge of the disc permitting the free downward movement of the pin 7 for weighing during the dribble feed and permitting the weigher to be controlled also in the upward movement of the receptacle.

In the constructions according to Figs. 1 to 4 the period of vibration or oscillation can be varied by shifting the centre of gravity, that is, by shifting the weight which gives the over-counterbalancing effect (29 in Fig. 4).

I claim:

1. In an automatic feed weigher of that type in which there is a main feed and a dribble feed the combination comprising a fixed frame, a movable receptacle, a shutter for said main feed, such shutter being adapted to close automatically upon the completion of the main feed, an unbalanced member pivoted upon said fixed frame, means upon said

movable receptacle cooperating with said unbalanced member to maintain said member out of balance until the termination of said main feed and means upon said unbalanced member to retard temporarily the downward movement of said receptacle to prepare the same for the dribble feed.

2. In an automatic feed weigher of that type in which there is a main feed and a dribble feed the combination comprising a fixed frame, a movable receptacle, a shutter for said main feed, such shutter being adopted to close automatically upon the completion of the main feed, an unbalanced member pivoted upon said fixed frame, means upon said movable receptacle cooperating with said unbalanced member to maintain said member out of balance until the termination of said main feed, means upon said unbalanced member to retard temporarily the downward movement of said receptacle to prepare the same for the dribble feed and means for damp the verticle reciprocation of said receptacle prior to the commencement of the dribble feed.

3. In an automatic feed weigher of that type in which there is a main feed and a dribble feed the combination comprising a fixed frame, a movable receptacle, a shutter for said main feed, such shutter being adapted to close automatically upon the completion of the main feed, an unbalanced member pivoted upon said fixed frame, said unbalanced member having a slot therein, a pin upon said movable receptacle cooperating with said slot to maintain said member out of balance until the termination of said main feed and said pin cooperating with an edge of said slot to retard temporarily the downward movement of said receptacle to prepare the same for the dribble feed.

4. In an automatic feed weigher of that type in which there is a main feed and a dribble feed the combination comprising a fixed portion, a movable portion, an unbalanced member pivoted upon said fixed portion, means upon said movable portion cooperating with said unbalanced member to maintain said member out of balance until the termination of said main feed and means upon said unbalanced member to retard temporarily the downward movement of said movable portion to prepare for the dribble feed.

5. In an automatic feed weigher of that type in which there is a main feed and a dribble feed the combination comprising a fixed frame, a movable receptacle, a shutter for said main feed, such shutter being adapted to close automatically upon the completion of the main feed, an unbalanced member pivoted upon said fixed frame, said unbalanced member having a slot therein having a recess therein extending toward the pivot point of said member and a pin upon said movable receptacle cooperating with said recess to main-

tain said member out of balance until the termination of said main feed.

6. In an automatic feed weigher of that type in which there is a main feed and a dribble feed the combination comprising a fixed frame, a movable receptacle, an unbalanced member pivoted upon said fixed frame, a pin upon said movable member, said unbalanced member having a slot therein with which said pin cooperates to retard temporarily the downward movement of said receptacle and a movable weight upon said unbalanced member whereby the speed of oscillations of said unbalanced member can be varied.

10 pivoted upon said fixed frame, said unbalanced member having a slot therein having a recess therein extending toward the pivot point of said member, a pin upon said movable receptacle cooperating with said recess

15 to maintain said member out of balance until the termination of said main feed and said slot having one edge thereof so disposed so as to cooperate with said pin to retard temporarily the downward movement of said receptacle to prepare the same for dribble feed.

7. In an automatic feed weigher of that type in which there is a main feed and a dribble feed the combination comprising a fixed frame, a movable receptacle, a shutter for said main feed, such shutter being adapted to close automatically upon the completion of the main feed, an unbalanced member pivoted upon said fixed frame, said unbalanced member having a slot therein having a recess

20 therein extending toward the pivot point of said member, a pin upon said movable receptacle cooperating with said recess to maintain said member out of balance until the termination of said main feed and said slot having the edges thereof so disposed as to cooperate with said pin to retard temporarily the downward movement of said receptacle and damp the vertical reciprocation of said receptacle to prepare the same for the dribble feed.

8. In an automatic feed weigher of that type in which there is a main feed and a dribble feed the combination comprising a fixed frame, a movable receptacle, an unbalanced member pivoted upon said fixed frame, a pin upon said movable member, said unbalanced member having a slot therein with which said pin cooperates, one edge of said slot cooperating with said pin to retard temporarily the downward movement of said receptacle and the other edge of said slot being cam shaped so as to increase said retarding action.

9. In an automatic feed weigher of that type in which there is a main feed and a dribble feed the combination comprising a fixed frame, a movable receptacle, an unbalanced member pivoted upon said fixed frame, a pin upon said movable member, said unbalanced member having a slot therein with which said pin cooperates to retard temporarily the downward movement of said receptacle and means for varying the speed of the oscillations of said unbalanced member.

10. In an automatic feed weigher of that

type in which there is a main feed and a dribble feed the combination comprising a fixed frame, a movable receptacle, an unbalanced member pivoted upon said fixed frame, a pin upon said movable member, said unbalanced member having a slot therein with which said pin cooperates to retard temporarily the downward movement of said receptacle and a movable weight upon said unbalanced member whereby the speed of oscillations of said unbalanced member can be varied.

In testimony whereof I have signed my name to this specification.

CARL DECKER.
